LEVEL WINDING DEVICE

Robert Paul Bigelow, Midland, Tex.

Application June 4, 1957, Serial No. 663,442

2 Claims. (Cl. 242—158.4)

This invention relates to level winding devices, and more particularly to devices for causing steel cable, such as a sand line used in well drilling, to spool up evenly on a hoisting drum.

In the winding of any flexible line upon a reel or drum, there is a tendency for the line to wind unevenly. This is objectionable in that it may cause the line to jerk or tangle when it is unspooled. Various devices such as level winders on reels for fish line and traveling guides for use in winding thread on bobbins of sewing machines have been proposed to remedy this condition.

In winding steel cable upon a drum, it is important that each layer extend from flange to flange. It is also important that successive turns of any one layer lay up close to one another and yet not pile up on top of one another close to the flanges. It is difficult to cause the successive turns to lay up close to one another, especially in well drilling operations where variations in load cause changes in the twist of the cable.

While devices have heretofore been proposed for solving the problem of properly winding steel cable on a drum, the general practice has been to place a man near the drum in a position where he can use a piece of pipe, a wrench, a crow-bar or the like to guide the cable on to the drum. This is, of course, hazardous. Moreover, it requires considerable guesswork and skill to so manipulate a tool as to cause cable to wind up properly on a drum.

Accordingly, it is an object of the present invention to provide a level winding device which enables an operation to be performed upon a cable as it is being spooled up on a drum as the result of which it will coil up closely and evenly all across the cylindrical surface of the drum from one flange to the other and yet not overlay or pile up adjacent the flanges. This is accomplished by providing a device which enables an operator to cause tension in the cable to place a slight lateral force or bias upon a sheave which is used to guide the cable on to the drum. The arrangement is such that the direction of the bias can be changed at will, so that as the direction of travel of the turns upon the drum is reversed, the guiding bias on the cable can be reversed. This is accomplished without the change in the angle with which the cable approaches the drum having any effect upon the amount of the bias, at least to any material extent.

Other objects and advantages of the invention will be apparent from a consideration of the following specification taken in connection with the accompanying drawings, in which:

Fig. 1 is a fragmentary perspective view of a drum and cable spooling mechanism with a level winding device constructed in accordance with the present invention applied thereto;

Fig. 2 is a perspective view of the shaft and sheave employed in the level winding device of Fig. 1, the sheave being shown in cross-section;

Fig. 3 is a vertical cross-sectional view of a portion of a shaft constructed in accordance with the invention and illustrating one way in which it might be made;

2

Fig. 4 is an end view of the shaft of Fig. 3; and

Fig. 5 is a somewhat diagrammatic illustration of a second embodiment of the invention in which hydraulic control means is employed for actuating a level winding device.

Referring to the drawing in detail, and first to the form of the invention shown in Fig. 1, it will be seen that a frame 10 is there illustrated with a drum 11 mounted thereon. A suitable engine (not shown) may be used to 10 rotate the drum, thus causing the cable 12 to be spooled upon it.

In accordance with the present invention, a sheath 13 is mounted upon the shaft 14 so as to be nearly tangential to the cable 12. The sheave 13 can slide freely back and forth upon the shaft 14 throughout the width of any layer of cable upon the drum.

As illustrated, the shaft 14 is located in front of the drum 11 so that the cable 12 plays under the sheave 13 as it is fed upon the drum. The mounting means for the 20 shaft 14 is such that its axis is approximately parallel to the axis of the drum 11. However, the mounting means is variable, so that the position of the shaft with respect to the frame 10 may be changed slightly, and so that the angle the axis of the shaft makes with the axis of the 25 drum may be changed slightly when desired.

In the embodiment of the invention shown in Fig. 1, the adjustment of position of the shaft is accomplished by its special construction. The shaft 14 is provided with trunnions 16 which are fitted into bearings 15 of the 30 frame 10. The trunnions 16 project diagonally from the ends of the shaft 14 at points spaced 180 degrees apart on the cross-sectional circle of the shaft, as shown in Figure 2. The shaft 14 may be made of one piece of steel, as shown in Fig. 2, or it may be made by welding 35 a piece of tubing on end plates 17, which are in turn welded to a trunnion shaft extending lengthwise therethrough, as illustrated in Figs. 3 and 4.

However constructed, the essential characteristic of the form of the invention of Fig. 1 is that the surface of the shaft 14 upon which the sheave 13 slides back and forth is eccentrically disposed with respect to the trunnions 16. Thus, by simply rotating the shaft 14, and without imparting any side thrust to the sheave 13 other than that imparted to it by the cable 12 itself, a small force or bias may be maintained on the sheave in a lateral direction 45 opposite to the travel of the turns of the cable on the drum, and that this bias can be maintained without any material variation until an entire layer of cable is spooled upon the drum. When one layer of cable on the drum is completed, the next layer is, of course, wrapped upon 50 it with the turns traveling in the opposite direction. This makes it necessary to reverse the direction of the bias on the sheave 13. Accordingly, some means is provided for rotating the shaft 14. One such means is illustrated in Fig. 1 as consisting of a worm and gear in a 55 housing 18. This mechanism may be keyed to one of the trunnions 16 and provided with a control wheel 20, so that by turning the control wheel the shaft 14 may be rotated.

It will be apparent that the mechanism in the housing 60 18 not only adjusts the position of the shaft 14 but that it positively holds it in an adjusted position regardless of the direction of the pull of the cable on the sheave 13. The adjusting mechanism is in no way responsive to the travel of the cable on the drum or to the particular location of a given turn of cable on the drum. It causes the cable to put a bias on the sheave 13, but the angle between the axis of the shaft 14 and the axis of the drum 11 remains constant during the wrapping of any given 65 layer on the drum, so that the magnitude of the bias remains nearly constant during the wrapping of the entire 70 layer.

Ordinarily, the shaft 14 will be rotated 180 degrees upon the completion of the wrapping of each layer of cable on the drum. However, it is obvious that the amount of bias on the sheave 13 can be controlled by varying the exact angular position of the shaft 14, and as the successive layers of cable build up to larger diameters on the drum, the degrees of rotation of the shaft may be varied to alter the amount of the bias.

Also, it should be mentioned that as such layer of cable is completed, it is desirable to have the first turn of the next layer up close to the flange of the drum. Hence, ordinarily, the shaft 14 should be rotated before that particular turn is laid. Thus, with the cable being fed upon the drum as illustrated in Fig. 1, the surface of the shaft 14 upon which the sheave 13 slides is closer to the drum on the right hand side than on the left hand side, so that a bias to the right is placed upon the sheave by the tension in the cable. In other words, the sheave is being made to travel up-hill on the shaft to the left, and this tends to hold each wrap of the cable on the drum up against the previous wrap. This condition will ordinarily be maintained until just before the last turn of that layer is completed. The shaft 14 should then be turned 180 degrees to cause the last wrap of that layer and the first wrap of the next layer to lay up close to the flange of the drum.

However, depending on conditions beyond the control of the operator, cable sometimes tends to pile up several layers close to the flanges on a drum, which is, of course, not desirable. When such conditions exist, it is clear that bias away from the flange should be maintained on the first wrap of each new layer. This can readily be accomplished with the device of the present invention by simply not rotating the shaft 14 until the first wrap of a new layer has been laid.

The device can, therefore, be operated to control the spooling of a cable properly under varying conditions and regardless of the changes in the diameter of the layers.

In the arrangement of Fig. 1, the axis of the surface of the shaft 14 may be said to swing about an imaginary pivot point midway between the extremes of the surface over which the sheave 13 slides. That is, with the shaft in the position shown, the right end of the shaft is near the drum and the left end farther away, but there is a point half way between the bearings 15, where the center line of the eccentric surface crosses the center line of the trunnions 16, which always remains the same distance from the drum. It is about this point that the shaft 14 swings when the gear in the housing 18 is manipulated.

The provision of means for causing the shaft 14 to swing about its midpoint is an important feature of the species of the invention shown in Fig. 1, since it means that there is a certain symmetry in the application of the biasing forces imparted to the cable by the sheave 13 regardless of whether the particular wrap of the cable on the drum is near one flange or the other or near the middle of the drum.

However, in its broader aspects, the invention is not limited to the provision of such mechanism as will cause the shaft to swing about its midpoint, and Fig. 5 illustrates a modification in which a shaft 21 is employed

which swings about a point near one end. Thus, it may be pivoted at 22 on a portion 25 of the frame. A sheave 23 slides back and forth on the shaft 21 to guide and put a bias on the cable 24 in a manner similar to that explained above in connection with the device of Fig. 1 as the shaft 21 is moved and held in a desired angular position with respect to a drum by a connecting rod 26 and a hydraulic power cylinder 27. Any suitable arrangement, such as the fluid lines 28 and control valve 29, with a handle 30, may be used to move a piston in the cylinder 27.

It is, of course, within the purview of the invention to use hydraulic means like that illustrated in Fig. 5 instead of the gear of Fig. 1 to actuate and hold an eccentric shaft like that of Fig. 1. Also, an electric motor could be used to adjust and hold a shaft in the desired angular position.

Various other changes may be made without departing from the spirit of the invention or the scope of the annexed claims.

I claim:

1. As an article of manufacture, a shaft suitable for use in a level winding device, said shaft having a cylindrical surface upon which a sheave may slide back and forth and two trunnions, one on each end of the shaft, said surface being eccentrically disposed with respect to the trunnions and said trunnions being diagonally spaced 180 degrees apart on said shaft whereby said surface will swing about an imaginary pivot point midway of its ends when the shaft is rotated on said trunnions.

2. In mechanism for spooling cable, the combination with a frame and a drum of a level winding device comprising a shaft, an arrangement for mounting the shaft on the frame in front of the drum with its axis approximately parallel to the axis of the drum, said arrangement including bearings fixed to the frame and trunnions fixed to the shaft, there being one trunnion at each end of the shaft, the trunnions being in line with each other but eccentrically disposed with respect to the cylindrical surface of the shaft and spaced 180° apart on the shaft, means for rotating the trunnions in the bearings thereby changing the angle of the axis of the shaft slightly with respect to the axis of the drum, a sheave rotatably mounted on the shaft and so arranged that it may slide back and forth on the shaft to guide the cable as it is fed onto the drum to wrap a layer thereon, and control means for positively adjusting the means for rotating the trunnions, regardless of the direction of pull of the cable, thereby causing the cable to place a slight bias on the sheave and causing a layer of the cable on the drum to be properly wrapped.
